ATTORNEY

UNITED STATES PATENT OFFICE.

CLEMENCE HOFFMAN, OF NEWPORT, MICHIGAN.

FOLDING CRATE.

1,268,715.

Specification of Letters Patent.

Patented June 4, 1918.

Application filed May 11, 1917. Serial No. 187,979.

To all whom it may concern:

Be it known that I, CLEMENCE HOFFMAN, a citizen of the United States, residing at Newport, in the county of Monroe and State of Michigan, have invented new and useful Improvements in Folding Crates, of which the following is a specification.

This invention relates to improvements in folding packing cases.

10 In carrying out this invention, my primary object is to provide a collapsible case wherein the parts are more rigidly and securely maintained in the erected position.

Another object is to facilitate collapsing and erecting the case.

15 Further objects are to simplify the manufacture of the case and to provide a more convenient and efficient arrangement of parts.

20 With these objects in view and others which will hereinafter become evident, I have embodied my invention in the form described in the specification, more particularly set forth in the claim, and delineated 25 in the drawings, in which—

Figure 1 is a perspective view showing the case partially assembled.

Fig. 2 is a side elevation illustrating the case in the collapsed condition as arranged 30 for shipping or storing.

Fig. 3 is an end view of the case in the collapsed condition.

Having more specific reference to the drawings, the case is represented in entirety 35 by the numeral 1, and comprises a bottom 2, a front wall 3, a rear wall 4, ends 5, and a top 6. To permit collapsing the case, the rear wall 4 is swingingly attached to the bottom 2 and the top 6 to the rear wall, 40 whereby in the collapsed condition the rear wall coincides with the inner surface of the bottom 2 and the top with the normally outwardly disposed face of the rear wall 4. The front wall 3 is adapted to fold under 45 the bottom 2, and the ends 5 are hinged to the adjacent portions of the front wall 3 for movement to a position in juxtaposition to the normally inward surface of said wall 3. The hinging connections may be of any 50 convenient form and comprise in the present instance hinges 7 and 8 whereby the bottom 2 is joined to the front and rear walls respectively, hinges 9 securing the top to the rear wall 4 and hinges 10 attaching the ends 55 to the front wall.

For more securely maintain the ends 5 in

the erected position, the hinges 10 are attached to the ends a suitable distance from the vertical edges 12, and the front wall 3 is formed with grooves or channels 13 60 adapted to receive the edges 12 in the outward movement of the ends, similar channels 14 being formed in the rear wall for receiving the opposite edges 15.

Means are provided whereby the ends 5 65 may be secured to the rear wall 4 to maintain the case in the erected condition. Such means comprise, in the preferred form of my invention illustrated, projecting portions 16 of the edges 15 adapted to engage openings 17 formed in the rear wall coincident with the channels 14 and terminally provided for retention in the openings 17 with rotatable wing-clamps 18 adapted to engage the outer surface of the wall in the 70 operative position.

To prevent relative movement of the parts of the case in the collapsed condition, I may provide the top with catches 19 adapted to engage eyes 20 on the front 3, and one 80 end-panel 5 with a similar catch 21 for engaging an eye 22 on the other panel. The usual hasp 23 on the top 6 and staple 24 on the front 3 enable the case to be locked when erected, and suitable hand-holds 25 85 are affixed to the end-panels 5 in the usual manner for convenience in moving.

In some instances, I may divide the interior of the case by a partition 26 secured in the erected case by insertion in channels 90 27 provided in the front and rear walls, and adapted to be disposed in the collapsed condition of the case between the bottom 2 and the front 3.

It is to be understood that the present embodiment of the invention comprises only one of many varied forms comprehended within the spirit of the invention, and I hereby reserve the right to such changes and alterations as may fall within the scope of 100 the appended claim.

I claim—

In a folding box, a bottom, a rear wall hinged to the bottom and formed adjacent each end with a transverse channel and with 105 openings coinciding with said channels, a top hinged to the rear wall, a front wall hinged to the bottom, said front wall formed adjacent each end with a transverse channel, end walls having front edges adapted to engage in said channels of the front wall and rear edges adapted to engage in said chan-

nels of the rear wall, projections on said rear edges adapted to extend through said openings of the rear wall, and clamps pivoted to said projections and adapted to be engaged against the outer surface of said rear wall, and hinge connections between the front wall and the end walls, said hinge connec-

tions attached to the end walls at points inwardly from the front edges of the end walls so that in the erected condition of the box 10 the front edges of the end walls will be engaged in said channels of the front wall.

In testimony whereof I affix my signature.

CLEMENCE HOFFMAN.
